[57] CLAIM

The ornamental design for a circular basket, as shown and described.

DESCRIPTION

FIG. 1 is a front isometric view of the circular basket in accordance with the invention, the rear isometric view being substantially a mirror image.

FIG. 2 is a side view of the circular basket with the handle folded down.

FIG. 3 is a bottom view of the circular basket.

FIG. 4 is a top view of the circular basket; and,

FIG. 5 is another embodiment of the circular basket without a handle.
